UNITED STATES PATENT OFFICE.

GEORGE M. EATON, OF PITTSBURGH, PENNSYLVANIA, ASSIGNOR TO WESTINGHOUSE ELECTRIC & MANUFACTURING COMPANY, A CORPORATION OF PENNSYLVANIA.

CAB-SUPPORTING STRUCTURE.

Application filed December 29, 1923. Serial No. 683,368.

My invention relates to railway vehicle structures, more particularly to the supporting of the cab member on its trucks.

It is among the objects of my invention to provide anti-friction sliding supports which shall eliminate the excessive wear that occurred in prior art structures, resulting from the relatively heavy cab structures being movably supported on the truck members.

Further objects of my invention are to provide anti-friction sliding supports for railway vehicle bodies which shall be of simple, compact and durable mechanical construction, which shall be adapted to maintain and provide a continuous film of lubricant on the engaging portions thereof and which shall be applicable to any standard railway vehicle.

The difficulty of maintaining adequate lubrication on the wearing plates or pads of railway vehicles has been a problem of great concern and long standing and has led to the use of various types of yielding and flexible mechanical devices, particularly center pin structures, which in some degree obviate these difficulties.

My present invention is directed to an anti-friction support that is provided with an inherent lubricating system for maintaining an oil film on the engaging faces of the wearing pads or plates at all times.

In the accompanying drawing constituting a part hereof and in which like reference characters designate like parts:

Figure 1 is a view partially in section and partially in elevation of a railway vehicle embodying the principles of my invention.

Fig. 2 is a view partially in section and partially in elevation of the supporting anti-friction member, and

Fig. 3 is a cross-sectional view thereof taken along the line III—III of Fig. 2.

Referring to Fig. 1, the structure herein illustrated comprises a familiar truck frame 1 that may be journalled on wheel axles 2 in the usual manner, as by means of journal boxes and side-frame pedestal construction (not shown). A transom member 3 is carried by the side frame 1, and a cab support 4 is secured centrally of the transom 3 to carry the cab or vehicle subframe 5.

The cab support 4, Figs. 2 and 3, comprises a base member or pillar 6 having a radial flange 7 that is provided with open-

ings 8 adapted to receive bolts 9, Fig. 1, by which the base is secured to the transom 3. The base 6 has a substantially cup-shape or recessed upper portion 10, the base of which is provided with integral trunnion seats 11, Fig. 3, which are adapted to receive the trunnions of a rocking disc or teeter plate 12. The teeter plate, as shown in Fig. 2, has a relatively thick central section and is reduced in size along the axis at right angles to the axis of the trunnions, for the purpose of providing angular or rocking movements of the plate about its trunnion axis.

The co-operating complementary or upper portion of the support 4 comprises a pedestal 15 that is secured to the cab frame 5 by a flange-and-bolt construction similar to that described in connection with the base 6. The pedestal 15 is provided with a radial flange 16 near its central body portion having a vertically depending ring or annular projection 17, which is adapted to seat in a groove 18 that is provided in the top rim of the base 6. The lower portion of the pedestal 15 extends within the cup-shape base portion 10 and is provided with an inverted recess 19 for securing a wearing plate or pad 20 that engages the teeter plate 12. The base 6 is also provided with a similar plate or bearing pad 20^a, which is located in a recess near the bottom of the cup-shape base portion 10.

The cup portion 10 of the base 6 constitutes an oil chamber or reservoir in which suitable lubricant is maintained at a level sufficient to cover the teeter plate and the co-operating bearing surfaces of the pads 20 and 20^a. The lubricant thus flows into the wedge-shaped crevices 21 formed in accordance with relative position of the teeter plate and the wearing pads, as determined by the motion of the cab member.

Under normal operating conditions of railway vehicles, a continuous swaying motion of the cab relative to the supporting trucks or rails occurs and, since the centerline of the trunnions is substantially parallel to the rails, the teeter plate is correspondingly rocked on its trunnions to alternately effect engagement of and expose its wearing faces. For every engagement of the bearing faces of the teeter plate with the wearing pads 12 of the support, a newly lubricated surface is provided, which greatly reduces friction and results in a minimum

wear of the co-operating bearing members.

Sliding of cab support plate occurs when the vehicle enters and leaves curves. With the trunnion centerline pointing toward the 5 cab centerpin, entry into curves will teeter the plate and leaving curves will again teeter the plate.

It is evident from the above description of my invention that cab supports made in 10 accordance therewith will provide an efficient and durable structure for adequately lubricating the several co-operating parts as an automatic function of its mechanical construction, thus making the lubrication of the 15 wearing surfaces inherent in the structure and independent of extrinsic means such as were commonly utilized in prior devices.

Although I have described a specific embodiment of my invention, it will be obvious 20 to those skilled in the art that various modifications may be made in the details of construction, the design and the proportion of the several co-operating parts, without de-

parting from the principles herein set forth.

I claim as my invention:

1. An anti-friction support comprising a base having a recessed portion, a teeter plate having integral trunnions seated in said base, a co-operating pedestal supported on said teeter plate, said plate having bevelled 30 faces, and a plurality of pads provided in said base and said pedestal for engaging said faces.

2. An anti-friction support comprising a base having a substantially cup-shape recessed portion for carrying oil, a teeter plate seated in said cup portion and a co-operating pedestal support seated on said plate, said plate having beveled faces adapted to engage the seating portions of said base and 40 pedestal.

In testimony whereof, I have hereunto subscribed my name this 22nd day of December, 1923.

GEORGE M. EATON.
